UNITED STATES PATENT OFFICE.

NATHAN WARSHAW, OF NEW YORK, N. Y.

INDEXING DEVICE.

Application filed September 5, 1925. Serial No. 54,838.

This invention relates to a class of devices for keeping memoranda for ready reference.

My invention has for its object primarily to provide a device designed to be employed for indexing desired memoranda, such as the names, addresses and phone numbers of persons, and which is of a form adapted to be applied on the transmitters of telephones or other suitable supports for convenient reference thereto as occasion may require. The invention resides mainly in the provision of a plate having a ring portion and having two alined spaced slots, and this plate may be mounted on a board element for being removably suspended from a suitable support, such as from the mouthpiece of the transmitter of a telephone. In the slots of the plate are a pair of removable resilient arches, each having preferably an arcuate body portion of spring metal for permitting the body to be compressibly moved to spring the free ends of the arch toward each other. On the ends of the body portion of each arch are clips or hooks which detachably grip the ends of the slot in which the arch is seated, and these arches serve to enable cards or the like to be removably mounted on the plate or board element for allowing the names, addresses and telephone numbers or other memoranda to be inscribed thereon for ready reference when wanted.

A further object of the invention is to provide an indexing device of a simple, efficient and durable construction which may be made in appropriate sizes and shapes.

With these and other objects in view, the invention will be hereinafter more fully explained with reference to the accompanying drawing forming a part of this specification in which similar characters of reference indicate corresponding parts in all the views, and will then be pointed out in the claims at the end of the description.

In the drawing, Figure 1 is a front elevation of a telephone with one form of indexing device embodying my invention applied thereto.

Fig. 2 is a fragmentary view showing an elevation of the upper portion of the device.

Fig. 3 is an enlarged sectional view, partly fragmentary and partly in elevation, taken on the line 3—3 of Fig. 2, and

Fig. 4 is a fragmentary view taken on the line 4—4 of Fig. 2 and which shows an enlarged side elevation of one of the catches used in the device.

The device may be provided with a board or surface element 10 which may be of any suitable size and shape, though the form of the board element illustrated has an approximately rectangular lower portion 11 and a curved or substantially semi-circular upper portion 12. In the upper portion of the board element is an opening 13 of preferably a circular shape, and in the board element in proximity to the lower part of the circular opening 13 are two spaced openings or slots 14, 15 disposed on alinement cross-wise of the board element. The element 10 may be of card board or other suitable material, and on one face of this element is a plate 16.

The plate 16 is preferably of metal, and the upper portion of the plate is formed into a circular ring, as 17, of a size so that it snugly fits the opening 13 of the board element 10. An annular flange, as 18, is provided on the inner edge of the ring 17, and this flange extends through the opening of the board element and is overlapped upon the second face of the board element for securing the element and plate together, besides providing a wear protector for the edge of the opening of the board element 10. In the plate 16 below the ring 17 are two spaced horizontally alined openings or slots 19, 20 which are in register with the openings or slots 14, 15 of the board element 10, and all of these slots are preferably vertically disposed. In the registered openings or slots are two removable arches 21, 22 which carry in suspended positions on the board element 10 one or a number of removable indexing slips or cards, as 25, for enabling desired memoranda, such as the names, addresses and telephone numbers or other data to be inscribed thereon for convenient reference thereto when wanted.

The arches 21, 22 are similar in shape and size, and each arch has a body portion 23 of spring metal of preferably an arcuate shape with its ends normally spaced apart at a distance similar to the length of each of the slots or openings 19, 20. On the ends of the body portion 23 of each of the arches are clips, as 26, 27, preferably hook shaped disposed with their openings in opposite directions, and these hook shaped clips are of a size so that they snugly grip opposite parts of the registered openings or the ends of the registered slots 19, 20 of the board element 10 and plate 16.

In the upper parts of each of the slips or cards 25 are holes through which are disposed the circular body portions 23 of the arches 21, 22. When it is desired to remove one or all of the cards 25 or add other cards thereto, both of the arches 21, 22 are removed from the board and plate elements by compressing the yielding body portions 23 of the arches, as shown in Fig. 4, sufficiently for disengaging the clips or hooks 26, 27 from the edges of the slots, and the arches with the cards may be detached from the board element and plate. One or more of the cards may then be removed from the arches or other cards may be mounted on the arches. The arches with the cards are afterward remounted on the board element by compressing the body portions 23 and inserting the hooked ends 26, 27 into the slots, and by releasing the pressure upon the body portions the hooks will engage the edges of the slots for holding the cards on the board element.

When the device is applied on the mouth piece, as A, of a telephone transmitter, as B, the ring portion 17 of the board and plate elements is arranged in encircling fashion over the mouth piece so that the cards and the board element will be suspended from the mouth piece. In the board element 10 slightly above the ring 17 of the plate 16 is a hole, as 28, and through the ring and this hole is held part of an elastic band 29 which is wrapped closely around the mouth piece for holding the device thereon to prevent it accidentally slipping from the mouth piece when the telephone is used if the ring 17 of the plate 16 is excessively larger than the mouth piece.

In the foregoing description, I have embodied the preferred form of my invention, but I do not wish to be understood as limiting myself thereto, as I am aware that modifications may be made therein without departing from the principle or sacrificing any of the advantages of this invention, there-

fore, I reserve to myself the right to make such changes as fairly fall within the scope thereof.

Having thus described my invention, I claim as new and desire to secure by Letters Patent:—

1. An indexing device comprising a board having an upwardly disposed extension with a circular opening therethrough, a metal protective plate on one face of the board and having a ring portion surrounding the opening of the extension of the board, said ring portion having on its inner edge an annular flange closely fitting the edge of the circular opening of the extension of the board; and said metal plate and extension having therethrough two horizontally spaced vertical slots adjacent the ring portion, and means in each slot for holding cards, said means including an arcuate spring strip with two oppositely disposed hook-shaped ends removably inserted in and spanning the ends of its respective slot.

2. An indexing device comprising a board having an upwardly disposed extension with a circular opening therethrough, a metal protective plate on one face of the board and having a ring portion surrounding the opening of the extension of the board, said ring portion having on its inner edge an annular flange closely fitting the edge of the circular opening of the extension, and said metal plate and extension having therethrough two horizontally spaced vertical slots adjacent the ring portion; a pair of arches for holding cards, each arch having an arcuate yielding body portion with two oppositely disposed hook-shaped ends and the hooks of each arch being removably inserted in and spanning the ends of each of said slots, and an elastic loop extending from the ring portion of said metal plate.

This specification signed and witnessed this 4th day of September, A. D. 1925.

NATHAN WARSHAW.
